COMBINATION SEAT AND INTERCHANGEABLE BACK

Joseph Martin, Laurelton, N. Y., assignor to
United States Cabinet Bed Co., Brooklyn, N. Y.,
a corporation of New York

Application June 10, 1940, Serial No. 339,617

5 Claims. (Cl. 5—47)

This invention relates to an improved combination seat and interchangeable back and support.

Among the objects of the present invention it is aimed to provide an improved combination couch bed or sleep-chair including a bed or seat member and an interchangeable member, interchangeable for the couch bed from back to bed formation, and for the sleep-chair from back to horizontal position.

It is still another object of the present invention to provide an improved control mechanism for a couch or chair back including a toggle and associated means which will anchor the back in erect position when the toggle is to one side of its dead center, and to anchor the back in horizontal position when the toggle is to the other side of its dead center.

These and other features, capabilities and advantages of the invention will appear from the subjoined detail description of specific embodiments thereof illustrated in the accompanying drawings, in which

Figure 1 is a perspective of a couch bed made according to the present invention, with the back in erect position;

Fig. 2 is a fragmental side elevation partly in section of the couch bed showing the back in erect position;

Fig. 3 is a fragmental front elevation partly in section of the couch bed with the back in erect position;

Fig. 4 is a fragmental side elevation partly in section of the couch bed with the back raised preparatory to reclining the same;

Fig. 5 is a fragmental side elevation partly in section of the couch bed with the back in horizontal position;

Fig. 6 is a plan of the couch bed with the back in horizontal position;

Fig. 6—A is an elevation of the front edge of the back.

Fig. 7 is a fragmental side elevation partly in section of the sleep-chair with the back in erect position;

Fig. 8 is a fragmental side elevation partly in section of the sleep-chair with the back in horizontal position and the foot rest in extended and raised position;

Fig. 9 is a fragmental front elevation partly in section of the sleep-chair with the back in erect position; and

Fig. 10 is a plan of the sleep chair with the back in horizontal position and the foot rest in extended raised position.

In the embodiment shown in Figs. 1 to 6A, there is illustrated a couch bed having a main frame 1 consisting of two side bars 2 and a front bar 3. The side bars 2 are connected to the end frames 4 and 5. On the side bars 2 and front bar 3 there is secured the main bed section 6 consisting of an upholstered portion serving as the seat portion of the couch in couch formation. The side bars 2 terminate in the present instance at a distance removed from the rear ends of the end frames 4 and 5, and in turn, the rear longitudinal side of the upholstered portion 6 terminates in the present instance at a distance removed from the rear ends of the side bars 2. 10 Immediately to the rear of the longitudinal rear side of the upholstered portion 6, there are secured the uprights or brackets 7 to the inner faces of the side bars 2. The uprights or brackets 7 are preferably composed of metal while the side bars 2 in the present instance are composed of wood.

To the upper inner ends of the uprights 7 there are pivotally connected the ends of the links 8 at 80, the outer ends of which links 8 are pivotally connected at 90 adjacent to one end of the vertically extending webs 9 of the angle irons 10, each link 8 extending rearward of its pivot point 80 in both back forming and bed forming position. To the other ends of the vertically extending webs 9, there are pivotally connected at 111 the upper ends of the levers 11 fulcrumed by the pins 12 to the opposite inner faces of the uprights 7, the upper arms of which levers 11 extending rearward of the fulcrum pins 12 in back forming position and forward of said pins 12 in bed forming position. The lower ends of the levers 11 in the present instance are connected to the tension springs 14 which are in turn connected to the inner faces 20 of the side bars 2.

The angle irons 10 have their webs 15 secured to the side bars 16 of the back forming section 17. The side bars 16 in the present instance are connected to the longitudinally extending bars 18 and 19, to the front face of which bars 16, 18 and 19 there is secured in the present instance the upholstered portion 20. Directly in front of the levers 11 and in the present instance substantially in alignment with the pins 12, there are provided the stop pins 21 extending inwardly from the uprights 7. At the middle of the inner longitudinal side 22 of the upholstered portion 20, there is provided the looped fabric handle 23.

As will now appear, the webs 9 will constitute

one set of the link members of toggles formed with the levers 11 as the other set. By means of these toggles 11, 9, links 8, stops 21, and handles 23, the interchangeable back 17 can with facility be guided into and out of back forming position and in turn into and out of bed forming position. As an instance, in the operation from bed forming position, that shown in Fig. 5, to the back forming position, that shown in Fig. 2, it is only necessary to engage the outer end of the back 17, Fig. 5, and raise it until the toggles 11, 9, have passed their dead centers and then permit the back 17 to descend when it will automatically seek the position shown in Fig. 2 where the lower arms of the levers 11 or portions of the levers 11 below the pins 12 will engage the stop pins 21 and enable the springs 14 to contract into the position shown in Fig. 2. In turn, when it is desired to swing the back 17 into bed formation, it will only be necessary to engage the handle 23, draw upwardly on the same in turn to draw upwardly the back 17, and thereby to draw the webs 9 upwardly until the dead centers of the toggles formed with the levers 11 will have been passed into the position shown in Fig. 4, against the tension of the springs 14, when the back 17 may be released automatically to descend into the bed formation shown in Fig. 5, where the upper arms of the levers 11 or portions of the levers 11 above the pins 12 will again engage the stop pins 21, see the position shown in Fig. 5, where the springs 14 will then again be extended as shown. While the stop pins 21 will determine the position of the back 17 in bed formation, in order to relieve the supporting strain exercised on such pins 21, especially when a person is resting on the back 17 in bed formation, there are provided the supporting elements consisting of the legs 24, the upper ends of which are pivotally connected to the bearing brackets 25 secured to the side bars 16 intermediate their ends, see Fig. 5, and in addition to the legs 24, the frame formed by the bars 15 and 18 also rests at its inner ends on the side walls 2. The free ends of the legs 24 are provided in the present instance with pivotally mounted feet or supporting elements 125. The legs 24 in turn have pivotally connected thereto adjacent the supporting elements 125, the outer ends of the bent links 26, the inner ends of which are pivotally connected to the opposite inner faces of the uprights 7 well below the pivot pins 12.

It will appear from Figs. 2 and 4, that the dead center of the pivot points 27, 28 and 29 of the legs 24 and links 26, where the pivot point 28 lies in a straight line between the pivot pins 27 and 29, can never be reached when moving from the final erect back formation, Fig. 2, through the intermediate position, Fig. 4, to the final bed formation, Fig. 5, and vice versa. In other words, the moment that the dead center of the toggles 9, 11, has been passed when moving from the position of Fig. 2 to that of Fig. 4, the further movement of the back 17 will tend to shorten the distance between the points 27 and 29, and therefore again cause the legs 24 to swing outward and finally into the position shown in Fig. 5.

The looped handle 23 extends down the front side of the upholstered portion 20 and is connected to the front edge of the longitudinally extending bar 18. It will be noted also that the fabric of the upholstered portion 20 extends down to the lower or outer face of the longitudinally extending bar 18 and has openings 81

formed therein in alignment with the front ends of the side bars 16 to accommodate the upper ends of the uprights 7 and working chambers for the links 8 and levers 11.

With the sleep-chair shown in Figs. 7 to 10 inclusive, the main frame 30 differs from the main frame 1 of the first embodiment in that the side bars or walls 31 are connected to one another by the rear bar or wall 32 with the space between the front ends of the walls 31 open, in the present instance to receive the foot rest or auxiliary extension bed section 33. In the present embodiment, the end walls 31 are connected to the end frames 34 and 35, and the front and rear bars 36 and 37 respectively have their ends secured to the upper edges of the side bars 31. The upholstered portion 38 is mounted on and secured to the bars 36 and 37, the front end of the upholstered portion 38 substantially aligning with the front edges of the end frames 34 and 35, and the end of the bar 37 and also of the upholstered portion 38 terminating forward of the uprights 39 secured to the inner faces of the walls 31 forward of the rear wall 32. The uprights 39 are connected to the interchangeable back member 40 by control means that are similar to the control means used with the first embodiment, except that the springs 14 and the legs 24 and links 26 of the first embodiment are omitted.

Here also, to relieve the extra pressure on the stop pins 41 in horizontal position of the back 40, when a person rests on the back 40 in horizontal position, the side bars 42 may be forced down so that the upper edges of the walls 31 and 32 will receive the side bars 42 of the back 40. In other words, when a person rests on the back 40 in the horizontal position shown in Fig. 8, the pressure on the pins 41 may be relieved by the back 40, when being strained, resting on the walls 31 and 32.

In the interest of the appearance of the article, the covering fabric of the back 40 will continue from the rear surface thereof down to and across the rear face of the wall 32, as shown in Fig. 7, with the fabric portion 43 straightening out in the erect position of the back 40 and drooping down into a loop in the horizontal position of the back 40, that shown in Fig. 8.

In the present embodiment for initiating the movement of the back 40 into horizontal position, there are provided two grips or fabric handles 44, 45, see Figs. 7 and 8, which extend down to the outer edges of the cross piece 145, one grip at each side of the front end of the upholstered portion 46 of the back 40.

Similar to the first embodiment, angle irons 47 are secured to the upper faces of the side bars 42 with the webs 48 extending upwardly in horizontal position of the back 40. Links 49 are pivotally connected at upper outer ends to the upper ends of the webs 48 in erect position of the back 40, and the inner ends of the links 49 are pivotally connected to the upper ends of the uprights 39. The inner ends of the webs 48 are pivotally connected to the upper ends of the levers 50 which are fulcrumed on the pins 51 extending from the inner faces of the uprights 39. Substantially in horizontal alignment with the pins 51 but inward of the levers 50, there are provided the stop pins 41 extending inward from the inner faces of the uprights 39. These pins 41, as shown in Fig. 8, engage the inner edges of the levers 50 above the pivot pins 51 in horizontal position of the back 40, and engage

the inner edges of the levers 50 below the pivot pins 51, as shown in Fig. 7, in erect position of the back 40. Here, too, in operation, the grips or handles 45, 46 singly or together, may be engaged in erect position of the back 40, swing the toggles formed by the webs 48 and levers 50 beyond their dead centers when initiating the movement of the back 40 into horizontal position, whereupon the back 40 will descend of its own accord into the position shown in Fig. 8; and in turn, when it is desired to initiate the movement of the back 40 back into erect position, it will only be necessary to engage the outer end of the back 40 and raise it until it again causes the toggles formed by the webs 48 and levers 50 to pass their dead centers in the opposite direction, when the back 40 will descend of its own accord into the final erect position shown in Fig. 7.

In order to form a day bed with the sleep-chair when dropping the back 40 into horizontal position, the extension bed section 33 may be extended into the position shown in Fig. 8. This extension bed section consists essentially of a lower frame having two side bar angle irons 52 with horizontal slots 53 in their vertical webs, an inner cross bar angle iron 54, and a front cross bar angle iron 55. To the front face of the vertically extending web of the angle iron 55 there is secured the front wall board 56. The lower frame so formed is slidably mounted on slidable angle irons 57. The angle irons 57 having horizontally extending slots 58, 59, are slidably mounted on the pins 60, 61 extending inwardly from the side walls 31 of the frame 30. The inwardly extending webs of the angle irons 57 support the outwardly extending webs of the angle irons 52 with the pins 62 extending downwardly from the front ends of the horizontally extending webs of the angle irons 57 to cooperate with the pins 63 extending horizontally outward from the rear ends of the vertically extending webs of the angle irons 52. The position of the pins 60, 61, length of slots 58, 59, and position of the pins 62, 63, relative to one another is such as shown in Fig. 7 to permit the lower frame to be completely housed in the chamber formed below the main upholstered portion 38 with the end board or wall 56 closing the chamber so formed as shown in Fig. 7.

The upholstered portion 64 of the foot rest or extension bed member 33 is mounted on the rectangular frame 65 having two side bar angle irons 66 to the rear of the vertically extending webs to which angle irons 66 there are pivotally connected the upper ends of the links 67. The lower ends of the links 67 are provided with pins 68 slidably mounted in the slots 53. In the forward portions of the vertically extending webs of the angle irons 66, there are formed the horizontally extending slots 69 in which are slidably mounted the pins 70 formed on the upper ends of the links 71, the lower ends of which links 71 are pivotally connected to the rear end portions of the angle irons 52. The links 67 and 71 are arranged in sets, one for each side of the extension bed section 33 and pivoted to one another approximately in the middle of each by the pins 72 as shown in Fig. 8. Preferably, the links 71 which are disposed on the inner faces of the links 67 are connected to one another by the cross piece angle iron 73.

The front ends of the links 67 have their pins 68 extending through the links 73, the front ends of which are connected to the ends of the arms

74 of the U-shaped supporting bracket 75, the arms 74 adjacent their bent portions 76 being pivotally connected as at 77 to the angle irons 52.

The rear ends of the links 71 are each connected by the tension springs 78 to the brackets 79 secured to the angle iron 54.

In use, the inward movement of the bracket 75 from the position shown in Fig. 8 to that shown in Fig. 7, will actuate the links 71 and 67 to lower the upholstered portion 64, in which operation the springs 78 prevent the sudden descent of the portion 64. Thereupon it is only necessary to push the end board 56 inward from the position shown in Fig. 8 to that shown in Fig. 7.

When preparing the device for use again, on the other hand, it will only be necessary first to draw outwardly the end board 56 and therewith the upholstered portion 64 and associated parts from the position shown in Fig. 7 to that shown in Fig. 8, and then swing the bracket 75 outwardly from the position shown in Fig. 7 to that shown in Fig. 8 when the springs 78 will aid in actuating the links 71 and 67 into erect position where they will raise the upholstered portion 64 to the position shown in Fig. 8 when the bracket 75 will be ready to engage the supporting floor and aid in supporting the extension bed section 33.

To eliminate undue friction and to steady the apparatus in its movement, the horizontally extending webs of the angle irons 57 are preferably provided with buttons 80 formed thereon on which the horizontally extending webs of the angle irons 52 ride as shown in Fig. 8.

It will also be obvious from inspection of Fig. 8 that when the bracket 75 has been drawn out into floor engaging position, its arms 74 will bring its pivotal connection with the links 73 below the straight line between the pivotal points 77 and 68 thereby to anchor the cross links 71 and 67 in erect position, the convex outer portions of the bent portions 76 in such position being wedged against the horizontal web of the angle iron 55.

It is obvious that various changes and modifications may be made to the details of construction without departing from the general spirit of the invention as set forth in the appended claims.

I claim:

1. The combination of a frame, a seat member secured to said frame, a back member having side bars, and means for connecting said side bars to said frame, each connecting means including a bracket secured to said frame extending upwardly adjacent the rear end of said seat member, a stop pin on each bracket, a lever for each bracket, each lever fulcrumed to one of said brackets with the end of one arm pivotally connected to one side bar and an edge of said lever below its fulcrum point engaging said stop pin in erect position of said back member and such edge of said lever above its fulcrum point engaging said stop pin in horizontal position of said back member, each side bar and associated lever forming a toggle positioned to one side of its dead center in erect position of said back member and to the other side of its dead center in horizontal position, and a link for each side bar, each link pivotally connected at one end to said side bar and at its other end to its bracket, the portion of each lever above its fulcrum point extending rearward in back forming position of said back member and extending forward in bed

forming position of said back member, and each link extending rearward in both back forming and bed forming positions of said back member.

2. The combination of a frame, a seat member secured to said frame, a back member having side bars, and means for connecting said side bars to said frame, each connecting means including a bracket secured to said frame extending upwardly adjacent the rear end of said seat member, a stop pin on each bracket, a lever for each bracket, each lever fulcrumed to one of said brackets with the end of one arm pivotally connected to one side bar and an edge of said lever below its fulcrum point engaging said stop pin in erect position of said back member and such edge of said lever above its fulcrum point engaging said stop pin in horizontal position of said back member, each side bar and associated lever forming a toggle positioned to one side of its dead center in erect position of said back member and to the other side of its dead center in horizontal position, a link for each side bar, each link pivotally connected at one end to said side bar and at its other end to its bracket, the portion of each lever above its fulcrum point extending rearward in back forming position of said back member and extending forward in bed forming position of said back member, and each link extending rearward in both back forming and bed forming positions of said back member, legs, each leg pivotally connected to one of said side bars, and connecting links, each connecting link pivotally connected at one end to one of said legs and at the other end to one of said brackets, the distance from the pivot point of a leg with its side bar to the pivot point of a connecting link with a bracket being greater than the distance from the pivot point of the side bar and one of said first named links to the pivot point of the lever and a bracket.

3. The combination of a frame, a seat member secured to said frame, a back member having side bars, and means for connecting said side bars to said frame, each connecting means including a bracket secured to said frame extending upwardly adjacent the rear end of said seat member, a stop pin on each bracket, a lever for each bracket, each lever fulcrumed to one of said brackets with the end of one arm pivotally connected to one side bar and an edge of said lever below its fulcrum point engaging said stop pin in erect position of said back member and such edge of said lever above its fulcrum point engaging said stop pin in horizontal position of said back member, each side bar and associated lever forming a toggle positioned to one side of its dead center in erect position of said back member and to the other side of its dead center in horizontal position, a link for each side bar, each link pivotally connected at one end to said side bar and at its other end to its bracket, the portion of each lever above its fulcrum point extending rearward in back forming position of said back member and extending forward in bed forming position of said back member, and each link extending rearward in both back forming and bed forming positions of said back member, and gripping means associated with the inner edge of the back member to swing such inner edge upwardly out of back forming position to

initiate changing said toggle from one side of its dead center to the other side of its dead center.

4. The combination of a frame, a seat member secured to said frame, a back member having side bars, and means for connecting said side bars to said frame, each connecting means including a bracket secured to said frame extending upwardly adjacent the rear end of said seat member, a stop pin on each bracket, a lever for each bracket, each lever fulcrumed to one of said brackets with the end of one arm pivotally connected to one side bar and an edge of said lever below its fulcrum point engaging said stop pin in erect position of said back member and such edge of said lever above its fulcrum point engaging said stop pin in horizontal position of said back member, each side bar and associated lever forming a toggle positioned to one side of its dead center in erect position of said back member and to the other side of its dead center in horizontal position, a link for each side bar, each link pivotally connected at one end to said side bar and at its other end to its bracket, the portion of each lever above its fulcrum point extending rearward in back forming position of said back member and extending forward in bed forming position of said back member, and each link extending rearward in both back forming and bed forming positions of said back member, and springs, each spring connecting the lower end of one of said levers with said frame to cushion said back member against a sudden descent into horizontal position.

5. The combination of a frame having wall members, a seat member secured to said frame with portions of said wall members exposed rearwardly thereof, a back member having side bars, and means for connecting said side bars to said frame, each connecting means including a bracket secured to said frame extending upwardly adjacent the rear end of said seat member, a stop pin on each bracket, a lever for each bracket, each lever fulcrumed to one of said brackets with the end of one arm pivotally connected to one side bar and an edge of said lever below its fulcrum point engaging said stop pin in erect position of said back member and such edge of said lever above its fulcrum point engaging said stop pin in horizontal position of said back member, each side bar and associated lever forming a toggle positioned to one side of its dead center in erect position of said back member and to the other side of its dead center in horizontal position, a link for each side bar, each link pivotally connected at one end to said side bar and at its other end to its bracket, the portion of each lever above its fulcrum point extending rearward in back forming position of said back member and extending forward in bed forming position of said back member, and each link extending rearward in both back forming and bed forming positions of said back member, the upper edge of said wall members being positioned just below the normal horizontal position of said back member to receive the back member in case of necessity to relieve the pressure on said stop pins when said back member is forced down below its normal horizontal position.

JOSEPH MARTIN.
